CLAIM

The ornamental design for the stereoscopic visualization apparatus, as shown and described.

DESCRIPTION

FIG. 1 is a top perspective view of the stereoscopic visualization apparatus;

FIG. 2 is a bottom perspective view of the stereoscopic visualization apparatus in FIG. 1;

FIG. 3 is a front elevational view of the stereoscopic visualization apparatus in FIG. 1;

FIG. 4 is a right elevational view of the stereoscopic visualization apparatus in FIG. 1;

FIG. 5 is a rear elevational view of the stereoscopic visualization apparatus in FIG. 1;

FIG. 6 is a left elevational view of the stereoscopic visualization apparatus in FIG. 1;

FIG. 7 is a top view of the stereoscopic visualization apparatus in FIG. 1; and,

FIG. 8 is a bottom view of the stereoscopic visualization apparatus in FIG. 1.

The ornamental design that is claimed is shown in solid lines in the drawings. The broken lines in the drawings are for illustrative purposes only and form no part of the claimed design.
